CONVERSION OF HYDROCARBON OILS

Bruce Sheppard, Bridgewater Township, Somerset County, N. J., assignor to Petroleum Conversion Corporation, Elizabeth, N. J., a corporation of Delaware

Application June 15, 1939, Serial No. 279,282

3 Claims. (Cl. 196—52)

My present invention relates to improvements in the art of hydrocarbon oil conversion.

Processes of hydrocarbon oil conversion have for some years been proposed in which the hydrocarbon material is passed through a reaction zone containing a solid contact agent, which by the action of adsorption or catalysts or decarbonization or otherwise, favorably affects the conversion process, either by increasing the yield or by improving the quality of the products, especially in the increased in antiknock value of the gasoline product. Considerable difficulty, however, has been experienced by reason of the fact that the solid contact agents become quickly coated with heavy tars or with free carbon, which prevent access of the hydrocarbon to the agent, especially by choking up the fine passages through the agent. To overcome this difficulty the proposal has been made to restore in situ the free surface of the contact substance by periodically burning out the tar or carbon. In so doing, however, the temperature of combustion is often high enough to affect the contact substance adversely, or to cause damage to the containing vessel, and in some cases the carbon can not be completely removed because of failure of the air to penetrate into the contact mass. Other attempts have involved the provision of molded contact masses in special containers with complicated devices for automatically cutting out a given contact mass, regenerating the same, and cutting in the regenerated contact mass, such arrangements involving great expense and unsatisfactory operation.

It is therefore a principal object of my present invention to overcome these difficulties by providing for substantially continuous movement of the contact substance during the conversion period, with the substantially continuous removal of the spent contact mass from the conversion zone, thereby obviating the necessity of regenerating the contact mass in the same apparatus which is used for conversion. In this manner fresh surfaces of contact substance are constantly presented in the conversion process, stoppage of the operation by deposition of carbon and tar is obviated, the capacity of the equipment for conversion is increased as the regeneration of the contact mass is conducted separately and in apparatus especially adapted for this purpose.

A further object of my invention is to facilitate the conversion reaction by providing for the introduction into the conversion zone of a hot inert gas, preferably a hydrocarbon gas, for both heating the said zone and for facilitating the re-

lease of the cracked products. A further object also is to provide for the preheating of the solid contact material prior to its introduction into the column or reaction zone, preferably by use of said hot gas. A still further object is to provide for circulation of the inert gas in a manner to prevent leakage of the conversion products either into the bulk supply of the contact material or into the accumulation of spent material from the conversion zone.

Other advantages and objects to be attained will be apparent as the description proceeds.

Referring to the drawings,

Fig. 1 is a view in side elevation, partly in vertical section, of an illustrative embodiment;

Fig. 2 is an enlarged view of a form of valve employed for moving the contact substance;

Fig. 3 is a side view of the device shown in Fig. 2.

Fig. 4 is a view in vertical section of a modified reaction chamber and valve for the contact material;

Fig. 5 is an elevational view showing the lower end of the reaction chamber, the valve employed and the upper portion of the hopper for receiving spent contact material;

Fig. 6 is a view on line 6—6 of Fig. 4.

In carrying out my invention I make use of a hopper for fresh contact material leading into a conversion chamber or column, desirably well insulated, a valve for controlling the flow of contact material through the reaction chamber, and a hopper for the spent contact material. In addition, means are provided for maintaining the proper temperature within the reaction chamber. For a complete understanding of the invention, reference is now made to the following detailed description of the illustrative embodiments.

Referring to Fig. 1, 10 is a hopper to be filled with the desired contact material, with the nature of which this invention is not concerned except that it be of a particle size as will flow freely and provide for the free passage of vapors therethrough, all as will be evident to those skilled in the art. Specific contact materials which have been successfully employed are silica gel, silica gel on which carbon has been deposited, silica gel on which aluminum oxide has been deposited, activated carbon of various kinds. Hopper 10 terminates in a neck or pipe 11 extending into the top of the reaction chamber 12 so as to provide a vapor space 13 above the level 14 of the contact material in said chamber. As shown in Fig. 1, the reaction chamber 12 com-

prises an inner wall 15 spaced from which is a jacket 16. Surrounding the latter is insulating material 17. Heating fluid is supplied within said jacket by inlet pipe 18 and exit pipe 19. Reaction chamber 12 terminates in a reduced portion 20 communicating with pipe 21 containing valve chamber 22, pipe 21 thereafter communicating with a hopper 23 for the spent contact material. Various other inlet and exit pipes are also shown, which will be referred to specifically during the description of the process.

As shown in Figs. 1 and 2, valve chamber 22 contains a valve 25 of the start type, the same being mounted upon a shaft 26 (Figs. 2 and 3) driven by motor 27 through reduction gears 28.

Hopper 23 is preferably provided with a pair of collinear sight glasses which may be of transparent quartz, one of which, 30, is seen in Fig. 1. Hopper 23 also has a discharge cover 31 and an inlet pipe 32 for inert gas for purging purposes.

In use, hopper 10 and conversion column 12 are filled with the contact substance in granular or pellet form or in lumps of graduated size, as may be desired, and the system completely closed off except for inlet line 32 at the bottom of the lower hopper 23 and inlet pipe 34 on upper hopper 10, whereupon flue gas, steam or other inert gas under suitable pressure is forced in by lines 32 and 34 to sweep air out of the system, the purge gas leaving by lines 35 and 36 and discharging into the atmosphere at the top of the reaction chamber. When the air has been displaced from the system the pipes 32, 34 and 36 are closed off by valves therein, as shown, and hot inert gas, preferably hot hydrocarbon gas, termed flash gas, is admitted through valved pipes 37 and 38. The hot flash gas may have a temperature of 850° F. more or less, and valve 39 in pipe 35 kept closed until the pressure in the system is built up to any desired value, for example, 10 pounds per square inch or 100 pounds per square inch, after which valve 39 is opened and flow continued through the contact material until the latter is brought up to substantially the conversion temperature. After the run is under way the flash gas admitted in 37 may be somewhat cooler than that stated in order that it may pick up heat from the spent contact material in and above pipe 21. Then while flash gas continues to be admitted through pipes 37 and 38, valve 40 in line 41 leading to the reaction chamber 12 is opened and oil vapor or a mixture of oil vapor and liquid oil from a suitable vaporizing system, not shown, admitted through said line (41). The mixture of vapors and gases leaves the conversion system by line 38. Pressure in the reaction chamber 12 is maintained slightly less than that of the gas admitted by pipes 37 and 38, as for example, 9 pounds per square-inch or 98 pounds per square inch, respectively, with 10 pounds per square inch or 100 pounds per square inch for the pressure of the flash gas. The slightly greater pressure of the hot gas as compared to the vapors insures that there will be no leakage of the vapors from the conversion chamber into either the hoppers 10 or 23, the vapors and gases leaving the reaction chamber through pipe 38. The vapors and gases from the line 38 pass to a recovery system (not shown), which separates the liquid products, fractionating them simultaneously as desired, yielding a lean gas substantially free of C₅ and heavier hydrocarbons, which lean gas may be heated and propelled to provide the flash gas for the system.

When the admission of vapors has reached

the desired rate, the star valve 25 is rotated at a uniform rate as by the motor 27 and gears 28. The motion of the star valve 25 transfers the contact substance from conversion chamber 12 through the receiver 28, at which time the column of contact material in chamber 12 gradually drops and fresh material from hopper 10 passes by way of pipe 11 into the conversion chamber. The operation is continued until the hopper 10 has been emptied, as may be determined by testing with a gauge rod 42, passing through a gland 42a. Preferably receiver 28 has sufficient capacity to hold the entire charge from the hopper 10 and conversion chamber 12. The condition of the charge in the system may be further ascertained by viewing through the peephole 30 in hopper 23.

During the operation of the system, heating fluid, as for example hot flue gas, is passed through the space between the inner wall of the conversion chamber 15 and the jacket 16 by admitting same through pipe 18 and removing it through pipe 19; or, if desired, flash gas may be used for this purpose, heat being conserved in the chamber by the insulating material 17. Desirably one or more additional inlets for hot gas may be provided throughout the column, one such inlet being indicated at 43. Occasionally some of the contact mass tends to stick in the star valve 25 due to adherent tars or soft coke. To remedy this, the supply of heated gas through pipe 37 may be increased by further opening the valve (37a) controlling same. Or, to prevent tars from reaching valve 25, hot gas may be admitted through pipe 44 immediately above valve 25.

When the run is completed, as determined by the fact that hopper 10 no longer contains any contact material, and by the fact that the receiver 28 is filled to the level of peephole 30, the admission of vapor through pipe 41 is stopped by closing valve 40, the admission of gas by lines 38 and 37 is continued to sweep all vapors out of the system, whereupon all valves excepting valve 39 are closed; and when the pressure has dropped, valve 39 is also closed. The system may then be purged and cooled by means of steam or cold flue gas using line 32 for admission and line 36 for discharge. When the cooling has been carried far enough to prevent spontaneous ignition of the carbon-loaded contact substance, bottom flange 31 is removed and the spent contact substance is permitted to drop into a car (not shown), and is transported into a regenerator which latter may consist of a rotary kiln or other device in which the contact substance is regenerated by burning with air. Top flange 50 is similarly removed, the hopper is filled with fresh contact material and the run repeated.

The temperatures employed in the reaction chamber are those which have been found to be best for this type of conversion, namely: 850° F.-950° F. for materials such as gas oil, 950° F.-1025° F. for such materials as straight run gasoline for reforming. If the conversion temperature is established at 850° F., for example, the temperature of the inert or flash gas may be 860-875° F., it being desirable to vary either the temperature or volume of the flash gas in order that the temperature of the exiting reaction products may be kept at a constant value during the run.

Fig. 4 shows a similar reaction chamber to that of Fig. 1 except that heat is supplied to the charge by means of an electric resistor 55 of

helical shape, as shown; in lieu of the heating jacket 16, said resistor being separated from the metal shell of chamber 15' by a thin layer of electrical insulating material, not shown. A valved inlet pipe 55a is also provided for admission of hot inert gas both for facilitating release of the reaction products and for further regulating the temperature in the reaction zone. In this figure a further type of discharge valve is employed, the same being the subject of a co-pending application filed August 2, 1939, Serial No. 287,891, in the name of William E. Joor, Jr. In this form of valve a flat approximately semi-circular plate 56, preferably about half the thickness of the distance between spacing plates 57 and 58 suitably secured together by means of devices 57a, is employed, the same being mounted for rotation in bearing 59 of plate 58, means for rotating same consisting of a motor 60 and gears 61. When spacing plate 58 is uncovered beneath the discharge end of the conversion chamber 12', the charge drops down thereupon, whereupon the deposited material is swept by leading edge 62 of said plate across the opening of pipe 21'. By use of this type of valve a minimum of crushing of the contact substance takes place. Any other type of measuring valve may be employed. It is also possible to operate the unit continuously by providing for the periodic admission to the hopper 10 of additional fresh contact substance and removal periodically from the receiver 23 of spent contact substance. Other variations in the process and apparatus will occur to those skilled in the art, without departing from the spirit of my invention.

Among the advantages of my improved method may be mentioned that fresh surfaces of contact substance are constantly presented for action in the conversion process, stoppage of operation by the deposition of carbon and tar is obviated, the capacity of equipment for conversion is increased as the regeneration of the contact mass is conducted separately, and the regeneration is simplified as that operation may be carried out in apparatus (not shown) especially adapted for this purpose.

I claim:

1. In the method of hydrocarbon oil conversion in which the conversion to other hydrocarbon compounds of different properties is brought about by pyrolysis in the presence of a solid contact material or agent, the improvement which consists of moving in a column said contact material from a source of supply through a conversion chamber and to a receiver therefor, introducing hydrocarbon vapor to be converted adjacent one end of said chamber, withdrawing converted products adjacent the other end of said chamber, supplying hot inert gas at points above and below the path of said vapors to be converted, said gas being supplied at a somewhat greater pressure than that existing in said chamber to prevent leakage of vapors of conversion from said chamber into said source of supply or into said receiver, said inert gas being at a sufficient tem-

perature and of adequate quantity to maintain the vapor in said chamber at its active conversion temperature, and withdrawing from said chamber said inert gas admixed with the converted vapor products.

2. In the method of hydrocarbon oil conversion in which the conversion to other hydrocarbon compounds of different properties is brought about by pyrolysis in the presence of a solid contact material or agent, the improvement which consists of moving in a column said contact material from a source of supply through a conversion chamber and to a receiver therefor, introducing hydrocarbon vapor to be converted adjacent one end of said chamber, withdrawing converted products adjacent the other end of said chamber, supplying hot inert gas at points spaced away from the inlet and outlet for the hydrocarbon vapor to be converted for the flow of said gas concurrently with the contact material entering said conversion chamber and countercurrently to the contact material leaving said conversion chamber, said hot inert gas being supplied at a somewhat greater pressure than that existing in said chamber to prevent leakage of vapors of conversion from said chamber into either said source of supply or said receiver, said gas being of quantity and temperature adequate to supply heat for the maintenance of the active conversion temperature of said hydrocarbon vapor, and withdrawing said gas admixed with said converted vapor products.

3. In the method of hydrocarbon oil conversion in which the conversion to other hydrocarbon compounds of different properties is brought about by pyrolysis in the presence of a solid contact material or agent, the improvement which consists of moving in a column said contact material from a source of supply through a conversion chamber and to a receiver therefor, introducing hydrocarbon vapor to be converted adjacent one end of said chamber, withdrawing converted products adjacent the other end of said chamber, supplying hot inert gas at points spaced away from the inlet and outlet for the hydrocarbon vapor to be converted for the flow of said gas concurrently with the contact material entering said conversion chamber and countercurrently to the contact material leaving said conversion chamber, said hot inert gas being supplied at a somewhat greater pressure than that existing in said chamber to prevent leakage of vapors of conversion from said chamber into either said source of supply or said receiver, said gas being of quantity and temperature adequate to supply heat for the maintenance of the active conversion temperature of said hydrocarbon vapor, and withdrawing said gas admixed with said converted vapor products, withdrawing a measured quantity of said contact material from said chamber, and prior to said withdrawal of said material introducing an additional stream of hot inert gas into said contact material to dry it just before its withdrawal from said chamber.

BRUCE SHEPPARD.
